Primary Examiner — Thomas Johannes*Assistant Examiner* — Chelsea Sealey(74) *Attorney, Agent, or Firm* — John R. Thompson; Stoel Rives LLP(57) **CLAIM**

I claim the ornamental design for a wallet portable electronic device case, as shown and described.

DESCRIPTION

FIG. 1 is a back perspective view of a wallet portable electronic device case showing my new design;

FIG. 2 is another back perspective view thereof;

FIG. 3 is a back perspective view with the back flap in an open position thereof;

FIG. 4 is a front plan view thereof; and,

FIG. 5 is a front perspective view thereof.

The dashed broken lines indicate stitching, which forms part of the claimed design.
